COLLAPSIBLE BOX

William Conescu, Brooklyn, N. Y.

Application June 11, 1934, Serial No. 730,085

1 Claim. (Cl. 229—34)

My invention relates to improvements in collapsible boxes, preferable of paper, card, fibre-board, card-board, corrugated paper or similar material, and more particularly has reference to 5 and is illustrated in the accompanying drawings in its application to a box of rectangular form adapted for use in cloak, suit, dress and similar lines.

Referring to said drawings, Fig. 1 illustrates, in 10 plan view, a suitable blank or blanks embodying an application of my invention. Fig. 2 is a view in perspective showing the blank shaped and folded in box form, one end being open. Fig. 3 illustrates the same in collapsed folded arrangement for stacking or carrying in stock, and Fig. 4 is a similar view showing modifications.

5 indicates the bottom of the box, 6, 7 the sides thereof, and 8, 9 the ends of the box. 10, 11 indicate the two halves of the top. 20 The top portion 10 and side 6 may be formed of two pieces as shown and may be stitched together as indicated at 12, or may be hinged by a piece of fabric as indicated in dotted outline at 13, or the side 7 and top portion 11 may be divided by a score line at 14, for folding or hinging the same. At each of the four corners is preferably provided an inwardly folding gusset portion such as 15, 16. The bottom of the box is also preferably hinged to the side and end portions 30 by score lines such as 17, 18, and the corner pieces are also preferably separated from the side and end portions by scorings such as 19, 20, said gusset portions also having radial scorings 21, and at the lateral margins of the top sections flaps or 35 tabs 21' to 24 inclusive may be provided, hinged by scorings 25. At the free ends of the box ends 8 and 9 are also preferably turned down portions such as 26, and the same, if desirable, may be slit at 27, 28 to provide three sections thereof indicated by reference characters 29, 30, and 31.

In forming or setting up the box, the free end portion 26 is laid over and stitched as indicated at 32 or, if formed of three sections as indicated at 29, 30 and 31, the outer sections may be stitched 45 as indicated at 33, leaving the inner section 30 free on the crease line 34, and in either case the crease line 34 is slit or cut through as indicated

at 35. When the side and end portions are turned up, the gusset in corners bend inwardly laying flat against the end portions of the box, after which the top portions may be turned over bringing the tab portions 21' to 24, inclusive, over the 5 slits 35, the same being bent at right angles to enter the slits, so that when the continuous flap 26 is used these tab portions are bound between the flap 26 and the end wall 8, whereas when the flap is divided in three sections as shown at the 10 right of the figure, the intermediate section 30 extends at right angles to the end wall 9, thus giving additional support and rigidity beneath the top portions 10, 11.

When stacking the boxes in stock, the top portion 10 may be turned outwardly from the center upon the side portion 6, as shown in Fig. 3, and the same applies to the top portion 11 which may be turned over on the side portion 7, or the top portions 10 and 11 may be turned under the side 20 portions 6 and 7, if desired, or, if preferable, the side or top portion such as 6 and 10 may be turned over as a whole in alignment upon the other side and top portion 7, 11, as shown in Fig. 4, the end portions and corner gussets extending flat as 25 shown, thus providing a convenient compact method of collapsing the box for stacking or carrying in stock.

Of course it will be understood that various modifications may be made in the construction, 30 form and arrangement of parts without departing from the spirit of the invention is claimed.

I claim:

A box of the class described, having a rectangular bottom portion and rectangular side, end and 35 top portions, each half of said top portion hinged to the upper edge of said side portions, and in combination with the lateral margins of said top portions, tabs adapted to engage with said end portions, said end portions having turned down 40 marginal portions with slits in one marginal portion to receive the other marginal portion, one of said marginal portions divided into three sections, inwardly folding gussets between said end and side portions, said top portions of separate 45 pieces of material hinged to said side portions.

WILLIAM CONESCU.
